WIRE REEL DISPENSERS

Abraham Madow, West Newton, Mass., and Hyman S. Glasband, West Hartford, Conn.

Application October 16, 1956, Serial No. 616,272

9 Claims. (Cl. 242—118.8)

The present invention relates to a wire dispenser and in particular to a roll-type dispenser and to a means for making the same.

The conventional wire dispenser now commercially used is conventionally made of metal or similar permanent material and is provided with a cylindrical core with two flanges positioned at the ends of the core and normal to it, the flanges being integrally secured to the core. This conventional type of wire dispenser is relatively expensive in view of the cost of the material and labor involved in its manufacture. Consequently, most dispensers of this type are re-used many times and give rise to cumbersome accounting systems involving both the wire manufacturers and their purchasers. It is an object of the present invention to provide a commercially acceptable throw-away dispenser made of inexpensive materials and by a simplified method of manufacture. In this connection, the present invention provides a roll-type dispenser of fiberboard, craftboard or similar material with the various components being cemented together into an integral unit.

The present invention also provides a method for assembling the components of the dispenser in a manner which is more efficient and rapid and less expensive than those previously known. The method practised further utilizes substantially all of the component parts of the dispenser without any portions of the die-cut elements being discarded as waste material. These and other objects and advantages of the present invention will be more clearly understood when considered in connection with the accompanying drawings, in which:

with the accompanying drawings, in which:

Figure 1 is a cross-sectional elevation of a cylindrical roll taken substantially through a diameter of the roll, and Figure 2 illustrates the embodiment of the invention shown in Figure 1 as viewed from the left side.

In the structure illustrated, the component parts of the invention may be made of any inexpensive material such as fiberboard, craftboard, cardboard or other similar material, provided the material is relatively stiff. Two end plates 1 and 2 and a center core or cylinder 3 form the essential and basic components of the dispenser structure. The end plates 1 and 2 are illustrated as being round. However, other suitable shapes may be used for these members, as well as for the cylinder 3, if desired. The end plates 1 and 2 each have a central portion or cover element 4 die cut from the remaining portions of the plates whereby the central portions 4 may be displaced from the plane in which the remaining or annular portions of the plates 1 and 2 are located. The periphery of the central portions 4 conform to the outer surface of the core 3 both as to size and shape. The center core 3 has its ends fitting into the openings in the plates 1 and 2 created by the displacement of the central portions 4. The ends of the core 3 project only substantially halfway through the thicknesses of the plates 1 and 2 and abut at their ends the inner peripheral surface of the central portions 4 which project beyond the outer surfaces of the plates 1 and 2. The core 3 is cemented

2

to the plates 1 and 2 at 5 and 6. The portions 4 are secured to the ends of the core 3 by cement located at points 8. This securing of the core and plates together as indicated may be accomplished by use of any suitable cementing means which will securely and rigidly hold the various components of the roll or spool together. Some cement should also be positioned between the adjacent sides of the central portions 4 and plates 1 and 2.

1 and 2.
10 The central portions 4 are provided with die-cut openings 9 and 10. Openings 9 are adapted to support the dispenser on a spindle for rotation in dispensing the roll from the reel, while the openings 10 are provided to receive a shaft or pin for causing the unit to turn at a
15 desired speed.

desired speed.

In forming these wire dispensers, two end plates 1 and 2 are die cut to any suitable and desirable shape, such as a disc as illustrated. Preferably simultaneously, the central portions of these end plates 1 and 2 are also die cut so as to be adapted to be punched out or displaced from the center of the main body of the end plates 1 and 2. At this initial stage, however, these central portions 4 are allowed to remain in the plane as their respective end plates 1 and 2. A core 3 of suitable length and having the same size and shape circumference as the central portions 4 is selected. A quantity of cement may then be placed about the die-cut opening forming the central portions 4 with the cement extending preferably inwardly from the die cut a marginal width equal to the thickness of the wall section forming the core 3. Preferably, however, cement is deposited on the end surfaces of the core 3. The core 3 is then positioned in direct alignment with the portion 4 and is uniformly moved towards it. The core 3 is then uniformly pressed partially through the end plates 1 and 2 at each end displacing from the plane of their respective plates the central portions 4. The core 3 should be forced through the tight-fitting end plates 1 and 2 to a point at which the portions 4 are displaced partially out of the plane in which they were formerly located. In this position, some cement will seep between the adjacent edges of the central portions and the plates 1 and 2. To accomplish this, suitable supports should be utilized which permit the displacement of the central portions 4 a selected distance from the plane in which the end plates 1 and 2 are located. This displacement will cause the cement to spread about the ends of the core 3 and the inner surfaces of the end plates 1 and 2 at points 5, 6 and 8. For this purpose, a relatively quick-drying cement should be utilized so that the end plates 1 and 2 will be rigidly secured in position once they are disposed about the core 3. In carrying out the method above suggested, the openings 10 in each center section 4 should be aligned one with the other for purposes of uniformity in structure.

This over-all method of producing the dispenser will provide a structure of substantial rigidity from inexpensive material with the process being adapted to be readily mechanized. Subsequent to this operation, a selected quantity of wire 11 may then be coiled in a conventional means about the dispenser.

It may be noted in connection with the cementing of the end plates to the core that the cut between the plates and central portion formed by the die is sufficient to permit the seepage of the cement between the plates 1 and 2 and the central portions as indicated above. The preferable way of applying cement is to apply it to the ends of the tubes so that the excess cement in addition to seeping down between the central portions and the plates as indicated above will also be positioned between the ends of the core and the inner surface of the central portions 4, thus providing further and substantial securing strength

to the entire structure. The strength which is obtained by cementing the roll dispenser in this manner is sufficient to avoid warping or bending of the plates with respect to the core or cylinder 3. In winding the wire onto dispensers of the type set forth above no arbor or adaptor is necessary to strengthen the end plates and thereby avoid warping or bending during the winding process as is common on dispensers of other types. A substantial portion of the strength imparted to the assembly as described above is obtained through the provision of a substantially greater area of cementing surface than has previously been obtainable in the structures heretofore known.

Having now described our invention, we claim:

1. A roll-type wire dispenser comprising a pair of parallel end plates each made of separable central and surrounding portions, said central portion of each plate being displaced outwardly partially out of the plane of the surrounding portion and forming a recess on the inner surface of each plate, and a core having its ends fitting tightly into the recesses and secured to both the central and remaining portions of the plates.

2. A roll-type wire dispenser comprising a pair of parallel circular end plates made of inexpensive fibre-board material, a circular cut formed in the center of each of the plates severing the central portions of the plates from the remaining portions of the plates, a cylindrical core having a diameter substantially equal to the diameter of the circular cuts and having its ends extending partially through the plates and displacing the central portions partially out of the planes of the remaining portions of the plates, and means securing the core to the central and remaining portions of the plates.

3. A roll-type wire dispenser comprising a pair of flat parallel end plates made of inexpensive rigid material, a circular cut formed in the center of each of the plates severing the central portion of the plates from the remaining portion of the plates, said central portions being displaced outwardly partially out of the plane of the remaining portions of the plates and forming a recess on the inner surface of each plate, and a cylindrical core having a diameter substantially equal to the diameter of the circular cuts and with its ends inserted into the recesses and abutting the periphery of the displaced central portions of the plates.

4. A device of the character described comprising a pair of flat parallel end plates each formed of an annular portion and a central portion fitting tightly within the annular portion, the central portion of each plate being displaced outwardly partially out of the plane of the annular portion and forming a recess on the inner surface of each plate, a core having ends fitting tightly into the recesses and abutting the inner surface of the central portions of the plates, and means securing the ends of the core in the recesses.

5. A device of the character described comprising a pair of end plates disposed in parallel planes and each formed from a single sheet of rigid material, the central portion of each plate being severed from the remaining surrounding portion and being displaced outwardly partially from the plane of the surrounding portion and forming recesses on the inner surfaces of the plates, a core having ends which fit tightly into the recesses and

5 abut against the inner surfaces of the central portions of the plates, means for securing the central portions in their displaced position to the surrounding portions of the plates, and means for securing the core to both the central and surrounding portions of the plates.

10 6. A roll-type dispenser of the class described comprising a pair of flat parallel end plates each having a separable round central portion, each of the central portions being displaced outwardly partially out of the plane of the remaining portions and forming recesses in the center of the inner surfaces of the plates, a cylindrical core having a diameter substantially equal to the displaced central portions and with its ends fitting into the recesses and abutting the periphery of the central portions, means securing the ends of the core to the periphery of the central portions and the sides of the recesses, and aligned central openings formed in the central portions of the plates and adapted to receive a shaft for supporting the dispenser.

15 7. A roll-type dispenser comprising at least one end plate divided into separable central and surrounding portions, said central portion being partially displaced from the plane of the surrounding portion and forming a recess in the plate, and a core fitting tightly into the recess and 20 abutting the displaced central portion, and means for securing the core, central portion and surrounding portion together.

25 8. A roll-type dispenser comprising at least one end plate made of separable central and surrounding portions, the central portion being displaced parallel to and partially from the plane of the surrounding portion of the plate, and a core disposed normal to the plane of the end plate with one end secured to the outer periphery of the central portion and the inner periphery of the surrounding portion.

30 9. A roll-type dispenser comprising at least one circular end plate made of inexpensive fiberboard material, a circular cut formed in the center of the end plate dividing the plate into separate central and annular portions, said central portion being parallel to and displaced partially out of the plane of the annular portion, and a cylindrical core disposed normal to the end plate and having one end secured to the marginal edges of the central and annular portions of the end plate adjacent to the cut.
